UNITED STATES PATENT OFFICE.

OLIVER F. WOOD, OF BALDWYN, MISSISSIPPI.

CAR-COUPING.

SPECIFICATION forming part of Letters Patent No. 255,748, dated March 28, 1882.

Application filed December 5, 1881. (Model.)

To all whom it may concern:

Be it known that I, OLIVER F. WOOD, of Baldwyn, in the county of Lee and State of Mississippi, have invented certain new and useful 5 Improvements in Car-Couplings; and I do hereby declare the following to be a full, clear, and exact description of the invention, such as will enable others skilled in the art to which it pertains to make and use it, reference being 10 had to the accompanying drawings, which form part of this specification.

My invention relates to an improvement in car-couplings; and it consists in pivoting in the lower end of the pin a supporting rod or 15 brace which will close up out of the way as the pin drops down into position, but which will automatically open when the pin is raised and form a support to hold the pin in a raised position, there being a recess formed in the 20 rear side of the pin to receive the rod when the pin is dropped, and a suitable shoulder or offset formed on both the rod and in the end of the pin to prevent the rod from falling too far forward, as will be more fully described hereinafter.

The object of my invention is to attach a support for the coupling-pin directly to the pin itself, so as to dispense with all such supports as are generally placed in the draw-head. 25 Figure 1 is a side elevation of my invention, partly in section. Fig. 2 is a front elevation of my invention.

A represents a draw-head, and B an extension which is formed upon one side. Rising 30 from the top of this extension is the standard C, in the upper end of which is pivoted the operating-lever D. This lever is long enough to be operated from the side of the car, or to have a chain, wire, or cord attached to its inner end, 35 so as to be operated from the top of the car, and thus do away with all necessity of the

brakeman having to go between the cars in coupling. To the inner end of this lever is attached the coupling-pin F, which has a shoulder, G, formed on its lower inside end or corner, for the purpose of catching over the link and holding it in position when the cars run together. In the rear side of the end of this pin is made a suitable recess, H, and in this recess is pivoted the supporting-brace I. This 45 brace is provided on its upper end with a shoulder, J, which abuts against a corresponding shoulder or projection, O, on the lower end of the pin, so that the brace can only drop downward a suitable distance. When the pin is 50 raised this brace drops downward, and, catching against the bottom of the draw-head, forms a support for the pin until the link enters and knocks the brace to one side. As the link is drawn backward against the rear edge of the 55 pin the brace is closed up in its slot and remains in that position until the pin is drawn upward by its lever. This brace, being pivoted directly to the pin, cannot be displaced while the cars are in motion or removed from 60 the draw-head, but is always ready for operation.

Having thus described my invention, I claim—

In a car-coupling, the combination of the 70 draw-head A, extension B, standard C, lever D, pin F, and rod I, the pin and rod being provided with shoulders O J to prevent the rod from falling too far forward, substantially as shown.

In testimony whereof I affix my signature in presence of two witnesses.

OLIVER FRANCIS WOOD.
